UNITED STATES PATENT OFFICE.

CHARLES W. HUNT, OF WEST NEW BRIGHTON, NEW YORK.

HOISTING APPARATUS.

SPECIFICATION forming part of Letters Patent No. 537,154, dated April 9, 1895.

Application filed February 11, 1895. Serial No. 537,886. (No model.)

To all whom it may concern:

Be it known that I, CHARLES W. HUNT, a citizen of the United States, residing at West New Brighton, in the county of Richmond and State of New York, have invented an Improvement in Hoisting Apparatus, of which the following is a specification.

Drums for actuating ropes or chains in hoisting apparatus are frequently driven by friction when drawing in the rope or chain, and allowed to revolve in the opposite direction when the weight is drawing off the rope or chain. Drums of this character have been made use of in elevating and excavating apparatus in connection with buckets or dredges, usually known as the clam shell bucket in which there are two halves hinged together, and closed by drawing upon the elevating rope, and opened by the weight of the bucket being suspended by a second rope or chain as the hoisting rope or chain is slackened.

The present invention is especially available in connection with buckets of the aforesaid character but not necessarily limited thereto.

Instead of having two drums separately actuated and requiring separate frictional devices, I make use of two drums controlled by friction in such a manner that it is only necessary for the attendant to make use of two regulating levers, or their equivalents, for controlling and directing the action of the power in operating the hoisting rope to close and elevate the bucket, and in opening the bucket for the discharge of its contents, and closing and lowering the bucket to refill the same, thus lessening the duties of the attendant, cheapening the construction of the apparatus and rendering the same more rapid in operation as well as more durable and easily kept in repair.

In the drawings, Figure 1 is a vertical longitudinal section of the drums and their actuating devices. Fig. 2 is a similar section with the parts arranged slightly different, and Fig. 3 is a diagram illustrating the connections to the elevating or excavating bucket.

A is a shaft supported in any suitable bearings and having upon it a wheel B that is driven by suitable power, such as by a pinion gearing into teeth upon the edge thereof,

by a belt or chain to the motor, or by frictional contact in any desired way.

C is the main hoisting drum to which the 55 rope or chain E is connected at one end or wound around the drum, and a suitable frictional connection F intervenes between the drum C and the driving wheel B, and adjacent to the drum C is the secondary drum G 60 for the rope or chain H, and there is a frictional connection at I between the drums C and G, which frictional connection may be of any desired character.

In Fig. 1 I have represented blocks of wood 65 intervening between the flat ends of the drums, and in Fig. 2 I have represented flat, metallic, frictional surfaces, and to this secondary drum G a frictional brake is applied of any desired character. I have represented 70 a strap K as passing around an annular flange upon the secondary drum, such strap being tightened or loosened by the action of a lever or other device of any desired character, and there is a spring L adapted to 75 press the secondary drum G toward the main drum C to obtain the necessary frictional contact between the friction devices I.

It is usually advantageous to permanently connect the drum C with the shaft A and to 80 allow the driving wheel B to remain loose upon the shaft A so that the driving wheel may be pressed toward the drum C for increasing the frictional contact F, there being a key 3 and pin 4 acted upon by a lever, 85 screw, or other device, as usual in frictional hoisting mechanism.

I have shown a screw at M actuated by a hand lever N for applying friction or relieving the same, and this hand lever or actuating device N and the lever for the frictional brake K, are the only two things that the attendant operates in controlling the movements of the drums.

The devices shown in Fig. 2 are the same 95 as those shown in Fig. 1 with the exception of the driving wheel B being keyed upon the shaft A so as to rotate with it, in which instance the drum C is loose upon the shaft A, and the drum is moved endwise against the 100 frictional contact F instead of the driving wheel being moved, and to effect this movement any desired appliances may be provided, such for instance as the key 13 and

the axial pin 14 against which the screw M is caused to act by the lever N.

- In using this device with a clam shell bucket, the frictional brake K is slackened 5 and the lever N applied to produce friction between B and C and rotate the drum C to draw upon the main chain or rope E to close such bucket and draw the same up, and the slack of the chain H is taken up at the same 10 time by the rotation of the secondary drum G by frictional contact with the drum C, and in order to prevent any slackness in the chain H it is preferable to make the drum G slightly larger than the drum C.
- 15 When the bucket has been raised to the desired height it is only necessary to hold the drum G by the frictional brake K and lessen the friction at F by turning back the lever N, and the weight will draw off a portion 20 of the chain from the drum C and the bucket opens to discharge the contents. The bucket can then be lowered by partially relieving the friction of the brake K, and in so doing the chains or ropes will be drawn off 25 both drums C and G, and when the bucket has been lowered to the extreme point, friction is again applied at F to the drum C to wind up the main chain E and close the bucket and draw the same up to the place of 30 delivery.

Where it is desired to close the bucket after discharging its contents, and before lowering the same, it is advantageous to apply a frictional brake to hold the drum C. I have represented the same in the form of a strap P around an annular flange upon the drum C so that after the bucket has been raised and its contents discharged, by transferring the weight to the rope or chain H by holding the 35 drum G by the brake K, the brake P can be applied to the drum C and the brake K relieved, so that the weight is transferred to the main chain E and drum C, and the lowering of the bucket is effected by the brake P, 40 the chains drawing off the drums as the weight descends, and then the weight is again transferred to the chain H just before the bucket reaches the bottom, by tightening the frictional brake K, and slackening the frictional brake P so as to open the bucket previous 45 to closing the same to grasp the load and draw the same up.

I claim as my invention--

1. The combination in a hoisting apparatus, 55 of two contiguous drums and means for driving the main drum, a frictional connection between the drums for driving the secondary drum, and a brake for controlling the secondary drum, whereby the secondary drum is 60 normally driven by the main drum and regulated by the brake, substantially as specified.

2. The combination in a hoisting apparatus, of a shaft and two drums on said shaft, and hoisting chains or ropes to the drums, a driving wheel and frictional connection between 65 the same and the main drum, and a hand actuated device for controlling such friction, a frictional device between the main and the secondary drums, and a hand actuated frictional brake to the secondary drum, substantially as and for the purposes set forth. 70

3. The combination in a hoisting apparatus, of a shaft and two drums on said shaft, and hoisting chains or ropes to the drums, a driving wheel and frictional connection between 75 the same and the main drum, and a hand actuated device for controlling such friction, a frictional device between the main and the secondary drums, and a hand actuated frictional brake to the secondary drum, and a hand actuated frictional device for holding the main drum and controlling the movement of the same as the rope or chain is drawn off, substantially as set forth.

4. The combination in a hoisting apparatus, 85 of a shaft and main hoisting drum therewith connected, a driving wheel loose upon the shaft, a frictional connection between the driving wheel and the main drum, a pin, key, and hand actuated device for controlling the 90 friction between the driving wheel and the main drum, a secondary drum on the same shaft, and frictional surfaces between the two drums, a spring for applying friction to such surfaces, a band and hand actuated mechanism for controlling the friction of the same in 95 stopping the secondary drum or allowing the same to rotate as the rope or chain is drawn off, substantially as specified.

5. The combination in a hoisting apparatus, 100 of a shaft and main hoisting drum therewith connected, a driving wheel loose upon the shaft, a frictional connection between the driving wheel and the main drum, a pin, key, and hand actuated device for controlling the 105 friction between the driving wheel and the main drum, a secondary drum on the same shaft, and frictional surfaces between the two drums, a spring for applying friction to such surfaces, a band and hand actuated mechanism for controlling the friction of the same in 110 stopping the secondary drum or allowing the same to rotate as the rope or chain is drawn off, a frictional strap and means for actuating 115 the same by hand to hold the main drum or control its movement as the rope or chain is drawn off, substantially as set forth.

Signed by me this 4th day of February, 1895.
CHAS. W. HUNT.
